ABRADING TOOL

Elmer Robbins, Portland, Oreg.

Application August 27, 1949, Serial No. 112,718

6 Claims. (Cl. 51—187)

1

This invention relates to an abrading tool of the type in which a strip of abrasive material, such as sandpaper is employed. More specifically, this invention relates to an abrading tool employing an endless belt of abrasive such as sandpaper and the like.

One object of the invention is to provide an improved holder for an endless belt of abrasive material in which the exposed portion or portions of the endless belt will be conveniently positioned for use and in which used portions of the belt can easily be replaced by unused portions so that full use of the entire abrasive surface of the belt will be obtained.

Another object of the invention is to provide a holder for an endless belt of abrasive material in which the belt can easily be mounted and in which such belt can easily and quickly be replaced.

A further object of this invention is to provide an improved abrading tool in which the abrasive material, as it is used, will be supported by a flexible blade, thereby rendering the tool more convenient, more practical and more efficient to use.

An additional object of this invention is to provide an improved abrading tool of the type above indicated which will be simple and inexpensive to manufacture, easy to assemble and handy to use and hold.

The manner in which these objects and other advantages are attained by the abrading tool comprising the present invention will be readily understood from the following brief description with reference to the accompanying drawings.

In the drawings:

Fig. 1 is a side elevation of my abrading tool showing the same entirely assembled and ready for use, with a portion of the side broken away and shown in section for the sake of clarity;

Fig. 2 is an exploded view in perspective showing the individual members separated from each other but arranged more or less in their relative positions;

Fig. 3 is a perspective view of the handle block by itself, the view being taken from a direction opposite to that in Fig. 2; and

Fig. 4 is a perspective view of the tool completely assembled and illustrating the tool in use.

In the different figures of the drawings, like references designate the same parts.

The body of the tool includes a handle block 10 which is preferably made of wood but which can also be made of metal, plastic or any other suitable material. The block 10 is formed and

2

shaped as shown in Figs. 2 and 3, the width being uniform throughout the block, but the thickness of the block preferably increasing from the inside end to the outside end as shown. The thicker end or outer end 13 of the block is substantially semi-cylindrical, the reason for which will later be apparent. A channel 11, the width of which corresponds to the width of the endless belt of sandpaper or other abrasive to be employed in the tool, extends along the top and bottom faces of the block 10 and around the semi-cylindrical outer end 13 as shown, the channel being bordered by a continuous ridge or flange 12 on each side. A transverse slot 14 through the block extends into the block from the inner or thinner end for a substantial distance, this slot 14 following the center line in each side of the block. An enlarged central cylindrical recess 15 (Figs. 3 and 10) also follows the slot inwardly.

A flexible metal blade 16, preferably made of steel, rectangular in shape, having a width substantially equal to the width of the channel 11 on the block 10, and having a thickness approximately equal to the slot opening 14, is adapted to have one end inserted in the slot 14 and to be longitudinally slidable therein. The inserted end of the flexible blade 16 has a cut-out portion or rectangular slot 17 in order to accommodate a coil spring 18 (Figs. 1 and 2). The length of the coil spring 18 normally exceeds the length of the slot 17 so that the coil spring will normally extend beyond the inner end of the flexible blade 16 when the blade is in place in the block 10. The outside diameter of the spring 18 is slightly less than the diameter of the central recess 15 in the block 10 so that the spring 18, as well as the inner end of the blade 16, will be longitudinally slid able in the block 10. When the blade 16 has its end inserted in the slot 14 of the block 10 with the spring 18 in place, the spring 18 will prevent any sidewise movement of the inserted end of the blade with respect to the block. However, the blade 16 can then be pushed still further into the block if sufficient force is exerted to compress the spring 18.

A single endless belt 19 of sandpaper or similar abrasive material is employed in my abrading tool. Similar endless belts of sandpaper are now commonly used in various machines employed for sandpapering. The width of the belt 19 is made approximately equal to the width of the channel 11 on the block 10, and the length of the belt 19 is such that when the belt is made to extend around the block 10 in the channel 11, the belt can be slipped over the outer end of

the blade 16, when the blade 16 and its spring 18 are in position within the block 10, by pushing the blade 16 a slight distance further into the block 10 against the force of the spring 18. When this is done and the belt is so mounted the belt 19 will be held stretched over the block 10 and over the outer tip of the blade 16 substantially as illustrated in Fig. 1.

The final member of my abrading tool to be set in place comprises a cover handle 20 which may be made of aluminum, thin steel, or any other suitable material having somewhat similar resiliency. The cover handle 20 is shaped as illustrated in Figs. 1, 3 and 4. It conforms in general to the shape of the block 10 and is made of the proper size to fit over the block 10. The block-covering portion of the handle cover has a continuous flange 21 on each side extending part way over the side faces of the block 10 so as to prevent the handle cover from slipping sideways off of the block 10. These side flanges 21 terminate near the inner ends of the block 10 when the handle cover is in place on the block. One end of the handle cover terminates in a short lip 24 which is bent slightly inwardly or towards the line of the blade 16. The other end of the handle cover is extended for a considerable distance so as to form a tongue 22 extending along over a portion of the belt 19 beyond the inner end of the block 10. This tongue portion 22 of the handle cover 20 then terminates in an outwardly curved lip 23.

When my abrading tool is to be set up, the flexible blade 16 with the spring 18 extending into the slot 17 is inserted in the block 10, as previously described. The endless belt 19 is then placed over the block and over the outer end of the flexible blade 16 which is pushed a slight distance into the block against the force of the spring 18 to enable the belt to be slipped over the outer end of the blade. Finally the handle cover 20 is slid over the block from the outer or enlarged end. In order to do this it is necessary for the handle cover to be opened wider, but the spring-like nature of the thin metal or other material from which the handle cover is made enables this to be done with little effort. When the handle cover is in place, as shown in Figs. 1 and 4, the lip 24 and the resiliency of the handle cover prevent the handle cover from sliding backwardly off of the block 10.

While any of the exposed surface of the abrasive belt 19 in my abrading tool can be used, the portion located on the under side of the blade 16 will be most frequently used, and in most cases it will be found convenient and preferable to use the tool in the position illustrated in Fig. 4. This will be the case particularly when a portion of an extended surface is to be subjected to the abrasive action. When my tool is so used the fact that the blade 16 is flexible is an important feature. The tongue 22 also has an important function, for, when the tool is so used the tongue not only enables increased pressure to be applied on and through the blade 16, but also keeps the abrasive belt held down against the top face of the blade, since otherwise when the blade is bent in the manner illustrated in Fig. 4, the upper section of the belt would seek a shorter straight line position between the outer tip of the blade 16 and the block 10, shortening the distance to be spanned and thus making the belt so loose on the blade that it would have a tendency to slip off the end of the blade. If added pressure on the work is desired the fore-

finger of the operator's hand can also be placed on the tongue 22, which results in a very firm as well as comfortable hand hold.

When a portion of the exposed abrasive surface of the endless belt 19 has been used up the belt can easily be moved so as to bring an unused portion into the same desired position. This moving or shifting of the endless belt on the tool can be done if desired without removing the handle cover, but it is done more easily if the handle cover is removed. By holding the tool on end and resting the outer end on the block or handle cover against a supporting surface and then pinching the blade 16 between the fingers and pressing it downwardly and further into the block 10 against the force of the spring 18, the resulting slack in the endless belt will enable it to be shifted on the tool with an easy pull.

Entire removal of the belt and replacement of the belt is done easily and quickly after the handle cover is slipped off. Due to the shape, construction, and arrangement of the members of my improved tool, no adjusting screws or clamps are required, and consequently my tool is simpler to set up and more inexpensive to manufacture than certain other types of sand-paper holders now found on the market, and in addition will be found especially convenient to use.

I claim:

1. In an abrading tool of the character described, a handle block, a flexible blade having one end movably and removably mounted in the inner end of said block, means for urging said mounted end of said blade outwardly in said block, an endless abrasive belt extending around said block and around the outer end of said blade, and a handle cover on said block extending over said belt on said block.
2. In an abrading tool of the character described, a handle block, said block having a rounded outer end, a flexible blade having one end movably and removably mounted in the inner end of said block, a spring element in said block engaging said blade to urge said blade outwardly when said blade is pushed far enough into said block to compress said spring, an endless abrasive belt extending around said block and around the outer end of said blade, and a U-shaped handle cover on said block, said handle cover having side flanges extending over the side faces of said block.
3. In an abrading tool of the character described, a handle block, said block having a rounded outer end, said block having a channel extending around over the top, bottom and outer end of said block, a flexible blade having one end movably and removably mounted in the inner end of said block, the width of said blade being approximately the same as the width of said channel on said block, an endless abrasive belt extending around said block in said channel and around the outer end of said blade, the width of said belt being approximately equal to the width of said channel, and a U-shaped handle cover on said block extending over said belt on said block, said handle cover having side flanges extending over the side faces of said block.
4. In an abrading tool of the character described, a handle block, said block having a semi-cylindrical outer end, said block being thicker at its outer than at its inner end, said block having a channel extending along two faces of said block and around said cylindrical outer end, a

flexible blade having one end movably and removably mounted in the inner end of said block, a spring element in said block engaging said blade to urge said blade outwardly when said blade is pushed far enough into said block to compress said spring, an endless abrasive belt extending around said block in said channel and around the outer end of said blade, the width of said belt being approximately equal to the width of said channel, and a spring-like handle cover on said block extending over said belt on said block, one of the inner ends of said handle cover terminating in an inwardly sloping lip, the other inner end of said handle cover terminating in a tongue portion extending along said belt beyond the inner end of said block.

5. An abrading tool of the character described including a handle block, said block having a rounded outer end, said block having a channel extending around said block, a flexible blade having one end movably and removably mounted in said block, the width of said blade being approximately the same as the width of said channel on said block, said block having a transverse slot extending into the inner end of said block, said end of said blade inserted in said slot, an endless abrasive belt extending around said block in said channel and around the outer end of said blade, and a U-shaped handle cover on said block extending over said belt on said block, said handle cover having a tongue portion extending along said belt beyond the inner end of said block and terminating in an outwardly curved lip.

6. An abrading tool comprising a handle block,

said block having a rounded outer end, said block being thicker at its outer than at its inner end, said block having a channel extending around said block, a flexible blade having one end movably and removably mounted in the inner end of said block, a spring element in said block engaging said blade to urge said blade outwardly when said blade is pushed far enough into said block to compress said spring, said block formed with a transverse slot extending into the inner end of said block and with an enlarged recess extending along the center line of said slot, said end of said blade inserted in said slot and said spring inserted in said recess, an endless abrasive belt extending around said block in said channel and around the outer end of said blade, the width of said belt being approximately equal to the width of said channel, and a spring-like handle cover on said block extending over said belt on said block, one of the inner ends of said handle cover terminating in an inwardly sloping lip, the other inner end of said handle cover terminating in a tongue portion extending along said belt beyond the inner end of said block.
